UNITED STATES PATENT OFFICE.

RAYMOND NOVINGER, OF CENTERVIEW, PENNSYLVANIA.

RAILROAD-FROG.

SPECIFICATION forming part of Letters Patent No. 734,132, dated July 21, 1903.

Application filed May 21, 1903. Serial No. 158,158. (No model.)

To all whom it may concern:

Be it known that I, RAYMOND NOVINGER, a citizen of the United States, residing at Centerview, in the county of Dauphin and State 5 of Pennsylvania, have invented a certain new and useful Railroad-Frog, of which the following is a specification, reference being had therein to the accompanying drawings.

This invention relates to railroad-frogs, the 10 object in view being to provide a simple, effective, and reliable frog in which the movable parts are rendered self-adjusting, the frog comprising a pair of wing-rails which are terminally pivoted at one end and which are 15 yieldingly held toward the point of the frog by means of a spring device which is located wholly between the wing-rails whereby said spring device is protected from injury and the operation of the wing portions of the rails 20 made certain and reliable.

With the above and other objects in view, the nature of which will more fully appear as the description proceeds, the invention consists in the novel construction, combination, 25 and arrangement of parts, as hereinafter fully described, illustrated, and claimed.

In the accompanying drawings, Figure 1 is plan view of a railroad-frog constructed in accordance with the present invention, showing the spring device partly in section. Fig. 2 is a cross-section on the line 2 2 of Fig. 1. Fig. 3 is a cross-section taken adjacent to the traveler or guide-bar.

Like reference-numerals designate corresponding parts in all figures of the drawings.

Referring to the drawings, 1 designates a base-plate of suitable size, the same being adapted to rest upon and be secured permanently to the ties of the road-bed. The point 40 2 of the frog is formed by the meeting extremities of the converging rail-sections 3, which are jointed and tenoned into each other, as shown at 4. Extending transversely through the rail-sections 3 is a traveler or 45 guide-bar 5, located a suitable distance above the base-plate and having its opposite end supported by means of blocks 6, which are interposed between the traveler-bar and base-plate, as best shown in Fig. 3. The traveler-bar 5 is held stationary and serves as a guide 50 for the wings of the wing-rails.

7 designates the wing-rails, which are terminally pivoted at 8 to a stay-bar 9, extending transversely of the track and secured to a tie or anchored in any other convenient manner. The wing-rails 7 converge toward the point of the frog and after extending beyond the point of the frog they are bent to flare outwardly in opposite directions, thereby forming the wings 10, which lie on opposite sides of the frog, the extremities of the wings being bent outward, as shown at 11, to insure the proper entrance of the flanges of the wheels between the wings and the point of the frog in a manner readily understood by 65 those conversant with the art to which this invention appertains.

At the points of junction of the wings 10 with the main body portions of the wing-rails 7 the latter are offset outwardly in opposite 70 directions, as shown at 12, and within said offsets 12 are securely fastened hard-metal reinforce-blocks 13, having their inner adjacent faces reversely beveled, the beveled faces forming continuations of and being exactly 75 in alignment with the corresponding inner edges of the wings 10 and the wing-rails 7, while the vertices 14 of the reinforce-blocks lie exactly opposite each other and close to the extremity of the point of the block, as 80 clearly illustrated in Fig. 1.

Between the wing-rails 7 is arranged a spring device consisting of a spring 14, arranged within a cylindrical spring box or housing 15 and a tension-bolt 16. The spring 85 box or housing 15 is bolted, as shown at 17, to the web 18 of one of the wing-rails, while the tension-bolt 16 is provided at one end with a head or shoulder 19, which engages the end of the spring, said bolt passing through 90 the spring and the spring-box and also through the web of the opposite rail, where it is held and made adjustable by means of a tension-nut 20. The spring device as a whole is located entirely between the pivoted wing-rails, 95 and is thereby protected from injury. The spring device exerts its tension to yieldingly hold the wings toward the point of the frog, at the same time allowing either one of the wings to yield away from the point of the frog 100 as a train passes over the same.

21 designates a pair of wing-rail checks or

stops, the same being securely fastened to the base-plate and being undercut to receive the base-flanges of the rail, as shown in Fig. 2.

Having thus described the invention, I claim as new—

A railroad-frog comprising a base-plate, a frog-point firmly fixed thereon, a fixed traveler-bar extending through the rails which terminate in the frog-point, a stay-bar, wing-rails terminally pivoted to the stay-bar and provided with wings which lie on opposite sides of the frog-point and also provided with offsets at opposite sides of the frog-point, re-

inforce-blocks held in said offsets and having reversely-beveled adjacent faces and oppositely-arranged vertices, and a spring located wholly between the pivoted wing-rails and acting to yieldingly hold the wings toward the frog-point, substantially as described. 15

In testimony whereof I affix my signature 20 in presence of two witnesses.

RAYMOND NOVINGER.
